UNITED STATES PATENT OFFICE.

ROBERT M. SUTHERLIN, OF KANSAS CITY, MISSOURI.

SPARK-INTENSIFIER.

1,205,682.

Specification of Letters Patent. Patented Nov. 21, 1916.

Application filed October 21, 1915. Serial No. 57,075.

To all whom it may concern:

Be it known that I, ROBERT M. SUTHERLIN, a citizen of the United States, residing at Kansas City, in the county of Jackson and 5 State of Missouri, have invented certain new and useful Improvements in Spark-Intensifiers; and I do declare the following to be a full, clear, and exact description of the invention, such as will enable others skilled in 10 the art to which it appertains to make and use the same.

This invention relates to improvements in spark intensifiers for spark plugs employed for internal combustion engines, and 15 the primary object of the invention is to provide an improved intensifier in which a short circuit is impossible and also having a novel form of adjusting screw which increases or decreases the spark.

20 A further object of the invention is to provide a device of this character which is simple, durable in construction, inexpensive to manufacture, and one which will be very efficient in operation.

25 With these and numerous other objects in view my invention consists of the novel features of construction, combination and arrangement of parts which will be herein-after referred to and more particularly 30 pointed out in the specification and claim.

In the accompanying drawings, Figure 1 is a side elevation; Fig. 2 is a central vertical longitudinal section; Fig. 3 is a horizontal section on the line 3—3 of Fig. 2; Fig. 4 is a central vertical longitudinal section 35 of a slightly modified form of my invention; Fig. 5 is a horizontal section on the line 5—5 of Fig. 4;

In describing my invention I shall refer 40 to the drawing in which similar reference characters designate corresponding parts throughout the several views and in which—

The numeral 1 designates an elongated flat metal link having apertures 2 and 3 adjacent its ends. This metal link 1 is adapted 45 to be secured to a spark plug of the ordinary type and ordinarily in a horizontal position, through the aperture 2 at one of its ends. The other end of the link is adapted 50 to receive a threaded bolt 4 which projects upwardly therethrough having its head positioned beneath the said link and its threaded shank projecting upwardly through the aperture 3 as clearly shown in Fig. 2 of the drawing.

55 A substantially circular shaped glass casing 5 has alined apertures 6 and 7 in its top

and bottom, and the aperture 7 in the bottom of the said casing receives the projecting shank of the threaded bolt 4. A portion of the shank of said bolt projects into the 60 recess in the said casing and is securely held therein by means of a locking nut 8 which has a threaded engagement with the said bolt to firmly and securely hold the link 1 into engagement with the bottom of the 65 glass casing 5.

The alined aperture 6 in the top of the casing 5 has its inner wall screw threaded, and is adapted to receive and securely hold 70 therein an externally threaded nut 9. This externally threaded nut 9 has a threaded bore 11 extending therethrough for a purpose to be hereinafter more fully described.

The bore 11 which extends centrally through the nut 9 in the top of the casing is 75 adapted to engage with the headless screw 12 which is considerably longer than the said nut and the said screw is normally engaged therewith adjacent its lower portion. The extreme lower portion of the headless screw 80 12 projects below the bottom portion of the nut, and is contracted to assume a frusto-conical shape as clearly shown in Figs. 2 and 4 of the drawings. This contracted or frusto-conical shaped end of the screw is 85 positioned a short distance above the threaded bolt 4 which projects upwardly through an aperture in the bottom of the glass casing and a spark gap is formed between the two ends in the said casing.

90 Positioned on the upper end of the screw 12 is any ordinary type of connection, whereby the same is connected or brought in contact with the batteries from which the source of current is derived. This connection which may be of the ordinary type used 95 is designated in the drawings by the numeral 13. The connection 13 is securely held in contact with the upper portion of the screw 12 by means of a pair of locking nuts 10 and 14, the nut 10 being adapted to engage the screw 12 and to be positioned on the top of the casing 5 at a point directly above the nut 9 in the aperture in the top of the same. The locking nut 14 is positioned above the locking nut 10, and the portion of the connection 13 which surrounds the screw 12 is thereby by this means firmly and securely held in contact therewith. This forms an easy and simple attaching 100 means, by which this connection is made.

105 Figs. 4 and 5 of the drawing illustrate a slightly modified form of this device, which 110

embody a slight change in the construction or shape of the aperture 6, in the top of the glass casing 5. In Figs. 4 and 5 of the drawing this top aperture which is designated by the numeral 15 is square, so that any desired form of nut 9 may be inserted therein. In the above mentioned figures is shown positioned in the squared opening 15 a circular form of nut similar to that inserted in the aperture 6 shown in Fig. 2, and this nut 9 is held in the squared opening 15 by means of cement 16, which surrounds the same and securely holds it in the above described position. If desired a nut correspondingly shaped to the said aperture may be inserted therein and locked by any desired form of cement or other desired locking means. It will be noted that the squared opening or aperture 15 will always be of sufficient size so that the circular nut 9 may be inserted therein should it be desired at any time.

The operation of this device is obvious, and in general outline is similar to the particular use in spark intensifiers effecting the broad characteristics of this device. The current is fed to this intensifier by means of the wire 13 and downwardly through the screw 12. The gap in this device is between the lower point of the screw 12 and the upper end of the bolt 4, which ends are positioned within the glass casing 5, and across which space the spark will jump when the current is fed to the screw 12 as above described. The current is carried through the link 1 to the spark plug which is attached to the end of the same. By this arrangement of parts a very simple and efficient form of spark intensifier will be formed which will prevent any possibility of a short circuit during the operation of this device. The glass casing which surrounds the spark gap of this intensifier is held firmly and securely in position against the jarring motion to which it is subject in use, and the frusto-conical form of the spark gap point of the screw 12 greatly increases its efficiency. The screw 12 is vertically adjustable through the central bore 11 of the circular nut 9, so that the same may be moved to different adjusted positions with respect to the end of the bolt

4, to increase or decrease the spark that is formed between the end of said screw and the bolt.

From the foregoing description of the construction of my improved device the manner of applying the same to use and the operation thereof will be readily understood and it will be seen that I have provided a simple, inexpensive and efficient means for carrying out the objects of this invention. The spark in this device is visible from any angle owing to the fact it is inclosed within a one piece glass casing or bowl and the device is free from danger of vaporized gas while in use. It is readily attached to automobiles, gas engines, motor cycles, aeroplanes, motor boats, and farm tractors, with perfect adjustment from a one sixty fourth to near one half inch which regulates and intensifies at will of the operator the current of old and new magnetos and batteries, producing perfect ignition when properly connected and regulated.

I claim as my invention:

A spark intensifier for spark plugs comprising an elongated flat metal link apertured adjacent its ends and connected at one end to a spark plug, a threaded bolt projecting upwardly through the aperture in the other end of said link, a substantially cylindrical shaped glass casing having aligned openings at its top and bottom, the bottom opening adapted to receive said bolt, a locking nut on the end of said bolt to securely hold the same in the casing, a centrally bored nut in the opening in the top of the casing, a screw positioned in the bore in said nut having a frusto-conical point spaced from the end of said bolt which is positioned in the casing, and adjustable locking nuts on the said screw above the said centrally bored nut adapted to secure a wire from the source of current in contact with said screw.

In testimony whereof I have hereunto set my hand in presence of two subscribing witnesses.

ROBERT M. SUTHERLIN.
